CLAIM

The ornamental design for a motorbike rear swing arm with mud flap, as shown and described.

DESCRIPTION

FIG. 1 is a top perspective view showing environmental structure of the top, rear, and right sides of a motorbike rear swing arm with mud flap;

FIG. 2 is a top perspective view showing environmental structure of the top, front, and left sides of the motorbike rear swing arm with mud flap;

FIG. 3 is a top perspective view showing the top, front, and left sides of the motorbike rear swing arm with mud flap;

FIG. 4 is a top perspective view showing the top, rear, and right sides of the motorbike rear swing arm with mud flap;

FIG. 5 is a right side elevation view of the motorbike rear swing arm with mud flap;

FIG. 6 is a left side elevation view of the motorbike rear swing arm with mud flap;

FIG. 7 is a front elevation view of the motorbike rear swing arm with mud flap;

FIG. 8 is a rear elevation view of the motorbike rear swing arm with mud flap;

FIG. 9 is a top plan view of the motorbike rear swing arm with mud flap; and,

FIG. 10 is a bottom plan view of the motorbike rear swing arm with mud flap.

The broken line showing of portions of the motorbike are provided for the purpose of illustrating environmental structure and form no part of the claimed design.

1 Claim, 6 Drawing Sheets
